UNITED STATES PATENT OFFICE.

ADOLPHUS LA BONTÉ, OF WORCESTER, MASSACHUSETTS.

APPARATUS FOR FLUSHING WATER-CLOSETS.

SPECIFICATION forming part of Letters Patent No. 655,303, dated August 7, 1900.

Application filed March 8, 1900. Serial No. 7,818. (No model.)

To all whom it may concern:

Be it known that I, ADOLPHUS LA BONTÉ, of the city and county of Worcester, in the State of Massachusetts, have invented certain new and useful Improvements in Apparatus for Flushing Water-Closets; and I do hereby declare that the following is a full, clear, and exact description thereof, reference being had to the accompanying drawings, forming a part

10 of this specification, and in which—

Figure 1 represents a central vertical section, partly in elevation, of my said improved flushing apparatus. Fig. 2 is a plan of said apparatus. Fig. 3 is a side or end view of the apparatus looking in the direction of arrow *a* in Fig. 2. Fig. 4 is a horizontal transverse section taken on line *b*, Fig. 3. Fig. 5 is a horizontal transverse section taken on line *c*, Fig. 3. Fig. 6 is a central vertical section through the upper part of the refilling-tank of the apparatus, which will be herein-after more fully described, this figure and all the following ones being shown upon an enlarged scale. Fig. 7 is a plan of the spring snap-catch and its operating cam-lever for holding the main operating-lever of the apparatus down while the water is flowing out of the main reservoir or tank until automatically released by the rise of the water in the

25 refilling-tank and the operation of said cam-lever, as will be hereinafter described. Fig. 8 is a side view of said spring snap-catch and cam-lever looking in the direction of arrow *d*, Fig. 7. Fig. 9 is an end view of the

30 snap-catch and cam-lever looking in the direction of arrow *e*, Fig. 7; and Fig. 10 is an interior view of the outlet from the reservoir or tank and its valve looking in the direction of arrow *f*, Fig. 1.

40 The object of my invention is to cover certain improvements upon the apparatus for flushing water-closets for which Letters Patent of the United States No. 624,224 were granted to me May 2, 1899; and it consists

45 of improvements whereby the construction of said apparatus is greatly simplified and whereby the amount of water discharged for both the main and after flush may be regulated, as will be hereinafter more fully set

50 forth.

To enable others skilled in the art to which my invention appertains to better understand

the nature and purpose thereof, I will now proceed to describe it more in detail.

In the drawings, *A* represents the main reservoir or tank, provided with the supply-pipe *A'* and which may be supported on suitable brackets *B* or in any other suitable and convenient manner.

C is the main flush-pipe, which is in practice connected at the bottom with the water-closet. (Not shown in this instance.)

D is the refilling-tank, arranged vertically at one side of the flush-pipe *C*, near its upper end, and connected at one side about midway in its length with the lower end of a conducting-pipe *E*, considerably smaller than the main flush-pipe and whose upper end is connected with an irregular-shaped casting *F*, forming the outlet of the main reservoir or tank *A* and to which said main flush-pipe is attached. Said refilling-tank *D* is also connected at or near its lower end with the main flush-pipe *C* by means of a short section of pipe or hub *G* of considerably-smaller diameter than the conducting-pipe *E*.

The aforesaid irregular-shaped casting *F* serves a triple purpose—viz., to form a water-passage from the outlet in the tank *A* to the main flush-pipe *D*, to also form a smaller water-passage to the conducting-pipe *E* and refilling-tank *D*, and to serve as a bearing for the mechanism for operating the valve at the outlet of tank *A*.

The upper end of the flush-pipe *C* is attached to the lower end of casting *F*—in this instance by means of an internally-threaded sleeve *g*, which is fitted over the right and left threaded ends *h i* of said casting and flush-pipe, the water-passage *j* extending in a curved line, as shown in Fig. 1, from the tank to the flush-pipe. The conducting-pipe *E* is also attached at its upper end to the casting *F* at one side of the flush-pipe connection, being in this instance screwed into an internally-threaded opening in said casting. From the upper end of said conducting-pipe a small independent curved water-passage *k* extends to, or nearly to, the outlet in tank *A* and unites with the main water-passage *j*, so that when the water is allowed to discharge from said tank part will discharge through the main passage *j* and part through the passage *k*, as and for the purpose hereinafter more fully described.

The discharge through the outlet in tank A is controlled by a valve H, which is opened by hand and closed automatically, as will also be hereinafter described. The discharge through 5 the small passage k is also controlled by a valve l, similar to those used on water and gas pipes for regulating the flow of water or gas therethrough.

Above the main water-passage j is formed 10 a horizontal longitudinal bearing for a short shaft I, which is fitted to turn therein. To the inner end of said shaft is secured the valve H, previously referred to, for controlling the discharge of water from tank A, and to its 15 outer end is secured the hub j' of the main operating-lever J of the device. Said lever is provided with a weight K at one end, and to its other end is attached the upper end of the usual chain L, employed for flushing the 20 water-closet. The chain end of the lever is pulled down to flush the closet, and the weight forces it back again to close the valve in the tank A, and thus stop the flush when said chain end of the lever is released. In order 25 that the movements of said lever and its valve H may be properly controlled, internally-projecting studs m n are secured in the end A² of the tank at the proper places for an arm H' on the valve to strike against the same 30 when the valve is swung around in either direction, as is indicated by full and dotted lines in Fig. 10.

When the chain end of lever J is drawn down and its weighted end elevated, as is shown by 35 full lines in Fig. 3, which is the position it occupies when valve H is open, said lever is held in said position by its bearing upon the under side of a snap-catch M until automatically released by forcing or drawing back 40 said snap-catch from over the same. This is done by the action of the water flowing through the small passage k and conducting-pipe E into the refilling-tank D, which as said water rises in said refilling-tank causes 45 a disk or float N, fitted horizontally therein, to be forced upward, and through a vertical connecting-rod O and cam-lever P forces said snap-catch back longitudinally out of action with said lever J, the vertical connecting-rod 50 being attached at its lower end to the hub of disk N and its upper end pivoted to the free end of the cam-lever P, which is in turn pivoted near its cam P' at P² to a fixed bearing Q on tank A. The snap-catch M is fitted 55 to slide longitudinally in said bearing Q, is provided with a suitable spring R for exerting a constant outward longitudinal pressure thereon, and is also preferably provided on its upper side with a friction-roll S for the 60 cam P' to impinge against, although, if desired, simply a projection or hub may be formed on the snap-catch spindle in lieu thereof. The cam P' is made wedge shape, with the thin edge at the bottom. (See Fig. 8.) 65 Therefore when it is moved down against the side of the friction-roll S by the water elevating disk N to raise the free end of lever

P the snap-catch is moved back and lever J released, as previously described. In order that the water in said refilling-tank may rise 70 therein to elevate the disk N and operate the snap-catch M to release lever J, as aforesaid, the outlet at the bottom of the refilling-tank and its short pipe G are made smaller than the supply-pipe E and passage k. Therefore 75 as the water flows into the tank it discharges from the bottom to refill the bowl of the closet and also rises in said tank to elevate disk N and release lever J to automatically shut off the discharge from the main tank A, as previously described, and after said shut off the water continuous to flow from the refilling-tank until emptied, and the closet thereby refilled ready for use.

In practice the amount of water discharged 80 at each flush may be regulated in three ways, either by varying the sizes of the supply and discharge pipes to and from the refilling-tank, by turning the valve l, or by both means combined—as, for instance, if a short flush is required the inlet E would be increased in size and the outlet G would be made smaller, so that the water discharged into the refilling-tank would rise faster than it discharges, and thus elevate the disk N and parts connected 85 therewith more quickly to shut off the discharge from the main tank A. In addition thereto the supply of water through pipe E to the refilling-tank may also be regulated by its valve k, so as to supply more or less water 90 through the pipe, and thereby vary the time of raising the disk N to release the lever J, or, if desired, the openings and pipes for supplying the water to and discharging it from the refilling-tank may in practice be made 95 alike for all apparatuses made in accordance with my invention and the duration of the flush controlled by simply turning the valve l, more water being allowed to pass through for reducing the amount of duration of the 100 flush and less water for increasing the amount and duration thereof.

In practice the apparatus is designed to be constructed and adjusted so that a flush will occur before the water reaches the upper end 105 of the refilling-tank D; but to provide against accidental overflow in case of derangement or improper adjustment of any of the parts I have arranged to securely close and make the opening D² in cover D', through which the 110 vertical rod O passes, perfectly water-tight by beveling the upper end N' of the hub of disk N and also correspondingly beveling the opening around said vertical rod O, so that when the disk N is elevated by the water the 115 bevel end N' will enter and close said beveled opening, as is indicated by dotted lines in Fig. 6.

The refilling-tank D is in this instance shown as being constructed of similar shape 120 to an ordinary house hot-water boiler, being made in the form of a cylinder with closed ends. It may be supported in position in any suitable and convenient manner, preferably 125

by means of a bracket or "clip" T, bolted to the upper end of the tank, passed around the flush-pipe C, and bolted in position, the bottom end being held in position simply by the 5 pipe connection G. The pipe E also contributes in a measure to the support of the tank.

By the construction adopted in my present invention I am enabled to dispense with the 10 ball-valve U employed in my previously-patented apparatus hereinbefore referred to, and I am also enabled to better control the amount or duration of each flush. It is also obvious that the general construction of the whole apparatus 15 is much more simple and compact, and I am therefore enabled to place upon the market a better apparatus, producing better results and at less cost than my said previously-patented apparatus.

Having now described my invention, what I claim therein as new, and desire to secure 20 by Letters Patent, is—

1. In an automatic apparatus for flushing water-closets, the combination of the main 25 tank A and flush-pipe C, with a casting F secured to said tank and flush-pipe, and having a water-passage in alinement with that of said flush-pipe, also having a smaller, supplementary water-passage k opening from the 30 main water-passage near its inner orifice, said casting also having a bearing for the shaft I, the refilling-tank D, said tank D being properly supported and connected at the bottom by a pipe G with the flush-pipe C; conduct- 35 ing-pipe E, connected at its upper end with casting F in alinement with the aforesaid supplementary water-passage k and at its lower end with the refilling-tank, above pipe G; the horizontal disk N, in said refilling-tank; ver- 40 tical rod O, attached thereto and pivoted to lever P; said lever P the same having the cam P' at its inner end; spring, snap-catch M, supported and fitted to slide longitudinally in a fixed bearing and having a projection for the cam P' to impinge against; weighted, operating-lever J, secured to the outer end of shaft 45 I and provided with means for operating it; said shaft I; the valve H secured to the inner end thereof and means for controlling the 50 movements of said valve and parts connected therewith, substantially as set forth.

2. In an automatic apparatus for flushing water-closets, the combination of the main tank A and flush-pipe C, with a casting F 55 secured to said tank and flush-pipe and having a water-passage in alinement with that of said flush-pipe, also having a smaller, supplementary water-passage k opening from the main water-passage near its inner orifice; the refilling-tank D, said tank D being properly supported and connected at the bottom by a pipe G with the flush-pipe C; conducting-pipe E, connected at its upper end with casting F in alinement with the aforesaid supplementary water-passage k, 60 and at its lower end with the refilling-tank above pipe G, and the horizontal disk N in said refilling-tank having the upper end of its hub beveled and attached to the bottom of rod O, which is in turn connected with the mechanism for automatically releasing lever J at the end of each flush, substantially as set forth.

water-passage k and at its lower end with the 65 refilling-tank above pipe G; the horizontal disk N in said refilling-tank; vertical rod O, attached thereto and pivoted to lever P; said lever P, the same having the cam P' at its inner end; spring, snap-catch M, supported and 70 fitted to slide longitudinally in a fixed bearing and having a projection for the cam P' to impinge against, substantially as set forth.

3. In an automatic apparatus for flushing water-closets, the combination of the main 75 tank A and flush-pipe C, with a casting F, secured to said tank and flush-pipe and having a water-passage in alinement with that of said flush-pipe, also having a smaller, supplementary water-passage k, opening from the 80 main water-passage, near its inner orifice, the valve L fitted in casting F across water-passage k for controlling the flow of water there- through; the refilling-tank D, said tank D being properly supported and connected at the 85 bottom by a pipe G with the flush-pipe C; conduct- 90 ing-pipe E, connected at its upper end with casting F in alinement with the aforesaid supplementary water-passage k and at its lower end with the refilling-tank above pipe G; the horizontal disk N in said refilling-tank; vertical rod O, attached thereto and pivoted to lever P; said lever P, the same having the cam P' at its inner end; spring, snap-catch M, supported and fitted to slide 95 longitudinally in a fixed bearing and having a projection for the cam P' to impinge against, substantially as set forth.

4. In an automatic apparatus for flushing water-closets, the combination of the main 100 tank A and flush-pipe C, with a casting F se- 105 cured to said tank and flush-pipe, and having a water-passage in alinement with that of said flush-pipe, also having a smaller, supplementary water-passage k opening from the main 110 water-passage near its inner orifice; the valve L fitted in casting F across said water-passage k for controlling the flow of water there- through; the refilling-tank D, said tank D being properly supported, connected at the bot- 115 tom by a pipe G with the flush-pipe C, and having its top end internally beveled around its central opening where vertical rod O passes through; conducting-pipe E connected at its upper end with casting F in alinement with the aforesaid supplementary water-passage k, 120 and at its lower end with the refilling-tank above pipe G, and the horizontal disk N in said refilling-tank having the upper end of its hub beveled and attached to the bottom of rod O, which is in turn connected with the mechanism for automatically releasing lever J at the end of each flush, substantially as set forth.

ADOLPHUS LA BONTÉ.
